US0D1050152S

(12) **United States Design Patent** (10) **Patent No.:** **US D1,050,152 S**
Beyranvand Nejad et al. (45) **Date of Patent:** **** Nov. 5, 2024**

(54) **DISPLAY SCREEN OR PORTION THEREOF WITH GRAPHICAL USER INTERFACE**

(71) Applicant: **10x Genomics, Inc.**, Pleasanton, CA (US)

(72) Inventors: **Ashkan Beyranvand Nejad**, San Jose, CA (US); **Caio Christovao Da Silva Porto**, San Jose, CA (US); **Katherine Habeck**, Belmont, CA (US); **Rushi Panchal**, Dublin, CA (US)

(73) Assignee: **10X Genomics, Inc.**, Pleasanton, CA (US)

(**) Term: **15 Years**

(21) Appl. No.: **29/843,974**

(22) Filed: **Jun. 24, 2022**

(51) LOC (14) Cl. **14-04**

(52) U.S. Cl.

CLAIM

The ornamental design for a display screen or portion thereof with graphical user interface as shown and described.

DESCRIPTION

FIG. 1 is a front view of a display screen or portion thereof with graphical user interface showing a first embodiment of the claimed design; and,

FIG. 2 is a front view of a display screen or portion thereof with graphical user interface showing a second embodiment of the claimed design.

The outermost broken lines showing a display screen or portion thereof form no part of the claimed design. The remaining broken lines showing the graphical user interface form no part of the claimed design.

1 Claim, 2 Drawing Sheets
